Richard E. Ericson, Keene, N.H., assignor to Elliot Laboratories, Inc., Fitzwilliam, N.H., a corporation of New Hampshire

Filed Aug. 3, 1967, Ser. No. 8,115

Term of patent 14 years

(Cl. D83—1)

FIG. 1

FIG. 2

FIG. 3

FIG. 1 is a front view of a urinary drainage bag, embodying my new design;

FIG. 2 is a view similar to FIG. 1 with the draw off tube in an alternate position;

FIG. 3 is a view as seen from the rear of FIG. 1;

FIG. 4 is a top plan view thereof with portions of the tubing fragmentarily shown for ease of illustration;

FIG. 5 is a bottom plan view thereof;

FIG. 6 is a left end elevation thereof; and

FIG. 7 is a right end elevation thereof.

The dominant features of my design reside in the portions shown in full lines.

I claim:

The ornamental design for a urinary drainage bag, substantially as shown and described.
